A. CUTTER.
MACHINE FOR FINISHING STAVES.

No. 104,121.

Patented June 14, 1870.

AMOS CUTTER, OF BOSTON, MASSACHUSETTS.

Letters Patent No. 104,121, dated June 14, 1870; antedated May 17, 1870.

IMPROVEMENT IN MACHINE FOR FINISHING STAVES.

The Schedule referred to in these Letters Patent and making part of the same.

To whom it may concern:

Be it known that I, AMOS CUTTER, of Boston, in the county of Suffolk, in the State of Massachusetts, have invented a new and useful Improvement in Machines for Finishing Staves for Barrels and Casks; and I do hereby declare the following to be a full description thereof.

In the drawing—

Figure 1 is a top plan view of the machine;

Figure 2 is a cross-sectional view; and

Figure 3 is a cross-sectional view, showing the staves on table B.

The object of this invention is to provide a machine that will chamfer, croze, and cut off the staves to any desired length, and finish the same ready to be set up into place in the cask; and

It consists in such construction of the machine as that the staves are automatically and securely fed from an inclined table, and presented to revolving saws and cutters that croze, chamfer, and cut the stave to the required length, gauge the depth of the crozing from the outside of the stave, and have the means of adjustment to work staves of different thickness; and

It also consists in the means of adjusting the crozing, chamfering, and cutting-off devices, as that any desired length of stave may be wrought and finished in the machine.

A A represents the frame that supports the operating parts of the machine.

B is an inclined feed-table, upon which the staves to be finished are placed on edge.

C C are two disk-wheels, which are made fast upon, and are revolved by means of a horizontal shaft, d, in the direction to feed the staves singly to the saws and cutter which croze, chamfer, and cut off the staves.

The disks C C are movable on shaft d, and are held in place by set-screws c' c'.

At suitable distances apart, and projecting from the periphery of the disk-wheels, are carriers e, which, as the disk-wheels revolve, come under and take hold of the edge of a single stave on table B, and carry the stave to the saws and cutter, which finish the stave complete.

D is a sliding frame placed upon the inclined table B, and in the rear of the staves to be acted upon, and is forced against the staves a by means of a spring, b, so that, as the disks revolve, a stave is taken up by the carriers, and when it is raised a little more than its width, the spring b forces the frame D and the staves a against the revolving disks, so that the next carrier will take another stave from the table to be presented to the saws and cutter, and so continue until the supply of staves on table B is exhausted, when the slide is forced back against the spring b, and another complement of staves placed on table B.

Frame D is made to slide easily in suitable guide-ways on inclined table B.

C C are guide-gauges placed concentrically over the disk-wheels C C, and extending one-third of the way, more or less, as may be desired, around the said disk-wheels, and so that as the carriers e revolve and carry a single stave, the outside of the stave will bear against the inside curvature of the gauge, which will hold the stave firmly as it comes in contact with the crozing, chamfering, and cut-off devices.

These guide-gauges are firmly and rigidly attached to sliding frames E E in such manner as not to give or yield to the outward pressure of the crozing, chamfering, and cut-off devices in finishing the stave, but will hold the stave so that the said crozing, chamfering, and cut-off devices will be ganged in their work by the outside of the stave bearing against the guide-gauges C' C', which will always secure a uniform finish of the stave from the outside thereof, which cannot be done when a flexible or spring guide or holder is employed.

E E are sliding frames working between the longitudinal plates of the main frame on proper guide-ways, and are located at both ends of the frame, and support the revolving, crozing, chamfering, and cutting-off devices.

These frames E E, with the revolving cutters and saws, are made to slide in the main frame, and be adjusted to any length of stave, by means of the screw-crash shafts e e going through appropriate nuts on the cross-plates of the main frame, thence to the cross-frames E E, where they are so attached as that they can be revolved in one direction, and move the frames E toward the center of the frame, and, by reversing the revolution, the frames E and the crozing, chamfering, and cutting-off devices will be drawn out from the center and allow a longer stave to be worked.

Frames E E, when adjusted to the proper places, which is known by the graduated scales A' on the top of the frame A, are held in such place by the rods e' e' and the set-screws e'' e''.

The crozing, chamfering, and cutting-off devices are formed together into a kind of cutter-head, and are composed of the crozing-saws f, chamfering-cutters f', and cutting-off saws f'', and attached to and revolve with shafts g g, which shafts are journaled in boxes g' and g'', have collars on each side of boxes g' to permit the box to slide with the shafts longitudinally while the shafts will slide freely in boxes g'', and the boxes remain fixed, which admits of the adjustment of the frames E, and the crozing, chamfering, and cutting-off devices.

Shaft d, that carries and revolves the adjustable disk-wheel C C, can be adjusted to different heights with relation to the guide-gauges C' C', crozing, chamfering, and cut-off devices, so that the thickness of the

stave outside of the crozing can be varied by turning the temper-screws *h*, which are underneath the sliding boxes *h' h''*, that carry shaft *d*. This is important, as it gives a ready means for working staves of different thickness by the same machine.

Motion is given to the revolving disk-wheels, and to the crozing, chamfering, and cutting-off devices by pulleys and belts, but in such manner as to revolve the carrier disk-wheels in the direction to carry the unfinished stave *a* to the devices *f, f',* and *f''*, for finishing, while the crozing, chamfering, and cutting-off devices revolve in the contrary direction.

The unfinished stave *a* is shown in fig. 1, on the table *B*, in broken lines, and *a'* in the same figure represents a finished stave, having been crozed, chamfered, and cut off to the right length, and is leaving the carrier disk-wheels and guide-gauges.

I am aware that spring-guides or holders have been employed in connection with carrier disk-wheels to hold the stave upon the disk-wheel, and against the devices that finish the stave, but such flexible holder in practice does not answer a good purpose, as, for instance, when the revolving tools strike into a hard stave or a hard knot in a stave, the spring holder will be unable to resist the force exerted by the saws and cutters to throw the stave outward, and, as a consequence, such staves will not be crozed or chamfered properly, by reason that it is thicker from the bottom of the crozing to the outside of the stave than it would have been had the guide-gauge been rigid and unyielding, as is fully shown in my improvement.

I am also aware that some means have been used for changing the devices for finishing staves, so that different lengths of staves may be finished in the same machine, but such means are confined to an adjustment at one end of the stave only, while in my invention such devices are adjusted at both ends of the stave, by which arrangement the force used for feeding the staves on the inclined table to the carrier disk-wheels, to always be applied to the center of the

length of the stave, making it always feed the staves evenly to the carrier-wheel, but where the machine has a capacity to work long and short staves, and is adjusted to the different lengths at one end only, the staves are not evenly fed to the carrier-wheels, as one end of the staves would receive more force to press it to the carrier-wheels than the other, causing the carriers, in some instances, to take hold of but one end of the stave, while the other end, not being in close contact with the disk-wheel, the carrier would not lift it from the table, and a general derangement would follow, but with my invention these difficulties are wholly and entirely avoided.

Having thus fully described my invention,

What I claim, and desire to secure by Letters Patent, is—

1. The disk-wheels *C C*, having the carriers *c*, in combination with the rigid unyielding guide-gauges *C' C'*, the crozing, chamfering, and cutting-off devices *f, f',* and *f''*, when they are attached to and adjusted by the sliding frames *E E*, constructed to operate in the manner described.
2. The inclined feed table *B*, and feeding frame *D*, in combination with the disk-wheels *C C*, having the carriers *c*, and the rigid unyielding guide-gauges *C' C'*, in the manner and for the purpose described.
3. The adjustable unyielding shaft *d*, and disk-wheels *C C*, having the carriers *c*, in combination with the rigid unyielding guide-gauges *C' C'*, and the crozing, chamfering, and cutting-off devices *f, f',* and *f''*, in the manner and for the purpose described.
4. The sliding frames *E E*, with their adjusting and holding devices, and carrying the crozing, chamfering, and cutting-off tools *f, f',* and *f''*, and guide-gauges *C' C'*, in combination with the graduated scales *A' A'*, for the purpose described.

AMOS CUTTER.
